[57] CLAIM

The ornamental design for a combined partition and ceiling unit for a store interior, as shown and described.

DESCRIPTION

FIG. 1 is a perspective view showing the design of a combined partition and ceiling unit for a store interior in accordance with the invention, as it would appear from the front;

FIG. 2 is a rear view thereof;

FIG. 3 is a top view;

FIG. 4 is a left side view, the right side view being essentially identical thereof; and

FIG. 5 is a bottom view.

FIG. 1

FIG. 2

FIG. 3

FIG. 4

FIG. 5
